UNITED STATES PATENT OFFICE.

FREDERICK WINK, OF PHILADELPHIA, PENNSYLVANIA, ASSIGNOR TO
THOMAS DOLAN AND R. WILLIAMS, JR., OF SAME PLACE.

DESIGN FOR SHAWL-PATTERN.

Specification forming part of Design No. **6,843**, dated September 2, 1873; application filed August 9, 1873.
[Term of Patent 3½ years.]

S.

To all whom it may concern:

Be it known that I, FREDERICK WINK, of the city and county of Philadelphia, State of Pennsylvania, have invented a Design for Shawl-Pattern, of which the following is a specification:

In the accompanying drawing, Figure 1 is a diagram, representing the relative arrangement of the parallel stripes A and B, of which my design for a shawl-pattern is composed; Fig. 2, an enlarged view of one-half of the stripe A; Fig. 3, a view of the stripe B.

The stripe A has a central bar, *a*, composed of three ornamental ribs, *x*, made up of dots and straight and angular dashes, between which are striped ribs *y*, of about the same width. The said stripe A has also a narrow ornamental rib, *b*, of the same character as

the central rib *a*, and a series of ribs, *d*, ornamented by groups of dots, these several ornamented ribs being separated by parallel plain ribs of different widths and shades or colors. The stripe B has a center, *e*, precisely similar to the center *a* of the stripe A, and is otherwise composed of plain parallel ribs.

Irrespective of the colors employed, I claim—

1. The design for the stripe A, as shown and described.
2. The design for the whole pattern, including the stripes A and B.

In testimony whereof I have signed my name to this specification in the presence of two subscribing witnesses.

Witnesses: FRED. WINK.
CLINTON M. LATOURETTE,
LEWIS T. GODFREY.
